UNITED STATES PATENT OFFICE.

EMIL JACOBSEN, OF PORT WASHINGTON, NEW YORK, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed November 4, 1918, Serial No. 261,003. Renewed July 23, 1924.

My invention relates in general to automatic telephone systems and more specifically to an improved method of operating automatic switches in such a system.

5 Among the objects of my invention are, to increase the capacity of the so called automatic switches, and to thereby cut down the initial cost of the installation of a system and to provide novel and highly efficient 10 mechanisms and circuits for controlling the same.

In order to accomplish the above results I have provided switches of nearly the standard type except that each switch has a plurality of sets of wipers mounted on the same 15 shaft and a switching relay which is arranged to switch the trunk circuit leading to the switch from one to the other of said sets of wipers. Each switch has as many 20 banks of 100 contacts as there are sets of wipers, and the sets of wipers move simultaneously to the corresponding sets of contacts in their respective banks. I also provide an impulse sender which delivers 25 twenty instead of the usual ten impulses. This sender is of course just like the usual well known types of sender except that it is larger and is capable of sending double the 30 number of impulses. In order to select a line in either or any bank of a switch, I have arranged the circuits so that the first 35 impulse to the line relay, causes an operation of the vertical magnet, which steps all the wipers to their first level, and the second 40 impulse, operates the switching relay to switch from the normally connected to the other set of wipers. This alternate operation of the magnet and switching relay continues until the desired level is reached. 45 Thus if the digit 2 is called the switch will step up one step and switch to the second set of wipers so that a trunk in the second level of the upper bank is selected. If 3 is called then the switch will first take a vertical 50 step, then switch to the second set and then take another vertical step and the switching relay falls back so that a trunk may be selected in the second level of the lower bank. In this manner although 20 impulses may be delivered to the switch, still the switch only takes the usual ten steps, 55 rotary and vertical and each alternate impulse is used to switch over.

I will now describe the operation of the circuits shown in the drawings which illustrate one embodiment of my invention. 55

Fig. 1 shows a calling substation A having a line switch C which has access to a number of selectors such as D.

Fig. 2 shows a connector H, which is one 60 of a plurality of similar connectors accessible to selector D, Fig. 1 and which is operated to extend a connection to a called line in any of four groups of 100 lines.

When the subscriber at A removes his 65 receiver to initiate a call, the line switch C is automatically operated in the usual manner to select an idle trunk line leading to a selector such as D. As soon as the relay 2 of switch C operates to cut the line through 70 to the selector, a circuit is closed for line relay 3 of selector D in series with the calling line circuit. Relay 3 closes a circuit for slow relay 4 to supply ground to the holding circuit of switch C and to prepare a 75 circuit for the vertical magnet 5 and series slow relay 6 at springs 7 and 8. Also when relay 3 energizes it opens the contact of springs 9 and 10 and closes springs 9 and 11.

Now when the calling device at substation A is operated for the first digit of the called number the relay 3 operates in accordance therewith to operate the switch in the following manner. As relay 3 falls back, a circuit is closed from ground through 85 springs 12, springs 9 and 10, springs 7 and 8, relay 6, springs 13 and 14, lower winding of relay 16, and magnet 5 to battery. Magnet 5 operates to step the wipers 17, 18 and 19 and 20, 21 and 22 to the first level 90 in their respective banks. Relay 6 remains energized and closes a circuit for relay 23 after the off normal springs 24 close to prepare a circuit for the rotary magnet 25. Relay 16, upon energizing over its lower 95 winding closes only the springs 28, as the lower winding is not strong enough to operate the rest of its springs. When relay 3 again energizes therefore ground is connected through springs 12, springs 9 and 100 11, springs 28, springs 27, and upper winding of relay 16 to battery. Relay 16 attracts its armature fully at this time, and closes a new locking circuit for itself through springs 26 and 27 to ground at 105 relay 4 and switches the circuit from relay

16 and magnet 5 through springs 13 and 15 to the upper winding of switching relay 29. The reason for this partial operation of relay 16 is to prevent any false operation of relay 29 before relay 3 has energized again, that is, springs 13 and 15 are not closed until springs 9 and 10 are disengaged. The next impulse from the line relay passes through springs 9 and 10, springs 7 and 8, relay 6, springs 13 and 15, and upper winding of relay 29. This upper winding of relay 29 is also weak and operates to close only the springs 30 which prepare a locking and stronger circuit for the lower winding of the relay. As soon as relay 3 again energizes this locking circuit is completed from ground through springs 31, springs 32 and 33, springs 30, and lower winding of relay 29 to battery. Relay 29 now operates to attract its armatures fully, opening the circuit of the relay 16 at springs 27, and switching the line and private conductors from the normal wipers to the line and private wipers 20, 21 and 22. Relay 16 falls back when its circuit is opened at springs 27 and again restores the circuit of magnet 5 and lower winding of relay 16 to the control of the line relay. It will be seen therefore that the first impulse operates the vertical magnet 5 and relay 16, while the second impulse operates relay 29 and restores relay 16 so that the third impulse again operates the vertical magnet and relay 16. Therefore, assuming the digit called to be 3, thus magnet 5 and relay 16 are first operated, then relay 29 is operated and relay 16 is unlocked, restores and relay 16 and magnet 5 are then again operated so that the switch has raised its wipers to the second level and stands with its line and private conductors connected to the normal wipers 17, 18 and 19. For the purpose of this illustration, however, we will assume that the digit 4 was called which operated the vertical magnet twice and the last impulse of which operated relay 29 to switch the conductors to the second set of wipers 20, 21 and 22. Now after the impulses for this digit cease and relay 3 comes to rest energized, when relay 6 falls back a circuit is closed for the rotary magnet 25 through springs 34, springs 35 and 36, and springs 37. Magnet 25 operates to step the wipers onto the first set of contacts in the elected level and also opens the springs 38 in the holding circuit of relay 23. Relay 23 falls back and opens the springs 37 to deenergize the magnet 25. Now if the first trunk line is busy and ground is present on the private contact, then current will flow over wiper 22, through springs 39 and 40, springs 41 and 42, springs 38, off normal springs 24, and relay 23 to battery. Relay 23 again energizes to close the circuit of magnet 25. This alternate operation of relay 23 and

magnet 25 continues until an idle trunk line is reached, at which time no ground is present on the private contact and no circuit is closed for relay 23. In this case relay 43 which has been heretofore short circuited energizes, over a circuit from ground through springs 34, relay 43, springs 38, springs 24, and relay 23 to battery. Relay 43, energizes alone over this circuit, being high wound, and operates to switch the line circuit through to the wipers, disconnects the line relay 3 therefrom, opens the springs 12, and connects ground from the switch ahead through private wiper 22, springs 39 and 40, springs 41 and 44, through springs 45 and 33 to the holding winding of relay 29, and through relay 43 and relay 23 to battery. Relays 43 and 29 are therefore held energized and the connection extended through to the connector H (Fig. 2). Line relay 47 of connector H energizes in series with the called line. The relay 47 is similar to relay 3 in its control of the magnets and switching relays, except that two switching relays are provided in the connector, one controlled during the vertical movement and the other during the rotary movement. Relay 47 closes a circuit for relay 48, which grounds the holding circuit for the switches C and D and prepares a circuit for the vertical magnet. As soon as the next digit or series of impulses are sent in, relay 47 responds thereto to close a circuit through springs 49 and 50, springs 51 and 52, springs 53, slow series relay 54, springs 57 and 58, lower winding of relay 55, and vertical magnet 56 to battery. Magnet 56 operates to raise the wipers to their first level of contacts, relay 54 holds energized during this series of impulses, and relay 55 being similar to relays 16 and 29 energizes only part way to close springs 59. It will be noticed that the connector has four sets of wipers instead of two and two switching relays, 60 and 61. If neither relay is energized, the line circuit passes to wipers 62, 63 and 64, if relay 61 alone remains energized, the circuit passes to wipers 65, 66 and 67, if relay 60 alone is energized the circuit passes to wipers 68, 69 and 70 and if both relays are locked energized the circuit passes to the fourth set of wipers 71, 72 and 73. After the line relay 47 comes to rest energized after the first impulse of this digit ground is connected through springs 49 and 74, through springs 59, springs 75, and upper winding of relay 55 to battery. Relay 55 now operates fully to open its lower winding circuit at springs 57 and 58, and prepares a new circuit for the lower winding of relay 60 through springs 57 and 76. Of course as soon as the switch takes its first vertical step the off normal springs operate to close one point in the circuit of the release magnet and to open the springs 130

53 and close the springs 77. As soon as relay 47 falls back for the next digit a circuit is closed from ground through springs 49 and 50, springs 51 and 52, springs 77, 5 springs 78 and 79, relay 54, springs 57 and 76, resistance 80, and lower winding of relay 60 to battery. Relay 60 energizes only part way to close the contact of springs 81 which prepare a locking circuit for its own 10 upper winding to the front contact of line relay 47. As soon as relay 47 pulls up again therefore, and springs 82 close, relay 60 operates fully through its strong upper winding and switches the line circuit and private 15 conductor to the wipers 68, 69 and 70. Also relay 60 opens the springs 75 in the locking circuit of relay 55 which deenergizes to again prepare the circuit for the magnet 56 and open the circuit of the lower winding 20 of relay 60. The next impulse again operates the vertical magnet and relay 55, and opens the locking circuit of relay 60. Thus the first, third, fifth etc. impulses operate the vertical magnet, while the second, 25 fourth and sixth etc. operate the switching relay 60 so that if the digit is an odd number the relay 60 will not be held energized, but if an even number is called then relay 60 will be held energized and will have selected either the first or second set of wipers, depending upon whether or not relay 30 35 40 45 50 55 60 65 70 75 80 85 90 95 100 105 110 115 120 125 130 61 is left energized during the rotary motion or final digit. After the impulses for this digit cease and relay 54 falls back a circuit is prepared for the rotary magnet 84. It will be assumed that the first digit was 4 and relay 60 now remains locked energized from battery through its lower winding through springs 87, springs 88 and 89, to ground, shorting resistance 80 and giving full power to relay 60. The subscriber now operates his calling device for the third and final digit of the called number thereby operating relay 47 with the following result: Each time relay 47 falls back a circuit is closed from ground through springs 49 and 50, springs 51 and 52, springs 77, springs 78 and 90, springs 91, relay 86, springs 92 springs 93 and 94, lower winding of relay 85, and rotary magnet 84 to battery. Magnet 84 operates to move the sets of wipers onto the first set of contacts in the fourth levels. Relay 85 upon energizing, the lower winding of said relay 85 being of high resistance, closes only the springs 95, which prepares an energizing circuit for the stronger upper winding of relay 85 which is completed at springs 49 and 74 when line relay 47 again energizes at which time relay 85 attracts its armatures fully to close a further locking circuit at springs 97 for its upper winding, opens the circuit of its own lower winding at springs 93 and 94, and closes at one point a circuit 65 for switching relay 61 at springs 93 and 96. Now when the line relay again falls back for the next impulse of this series a circuit is completed for relay 61 from ground through springs 49 and 50, springs 51 and 52, springs 77, springs 78 and 90, springs 91, 70 relay 86, springs 92, springs 93 and 96, and lower weak winding of relay 61. Relay 61 operates at this time to close only the springs 98 to prepare a circuit at one point in the circuit of its upper winding so that 75 when relay 47 again energizes to close springs 82 in this circuit relay 61 will attract its armatures fully to switch the line and private conductors to the line and private wipers 71, 72 and 73, and also to open 80 the springs 99 in the locking circuit of the relay 85 which relay now falls back, opens the initial energizing circuit of relay 61 and again prepares the circuit of the rotary magnet 84 at springs 93 and 94 so that when line 85 relay 47 operates for the next impulse the wipers are stepped to the next set of contacts in a manner previously described and relay 61 is again deenergized when springs 90 95 100 105 110 115 120 125 130 82 open. Relay 85 again prepares a circuit for relay 61 so that the fourth and last impulse of this series energizes relay 61 in the manner before described to again switch the line and private conductors to their alternate sets of line and private wipers. Therefore, it will be seen that these four impulses of the final series leave the switch with its wipers on the second set of contacts in the fourth level and with relays 60 and 61 both locked energized so that the line circuit extends through the front contacts of said relays to the wipers 71, 72 and 73 and a connection is therefore extended to that line which terminates in the second set of contacts in the fourth level of the upper of the four banks of contacts. Relay 86 has of course held energized during the alternate operation of magnet 84 and relay 61 and therefore holds the private wiper 72 in connection with the winding of the busy relay 100 for an instant so that if the called line is busy and a ground is present thereon relay 100 will lock energized to connect a busy tone to the calling subscriber's line. However, if the called line is idle relay 100 will not energize, and upon relay 86 falling back, a circuit is closed for wiper cut on relay 101 from battery on the called line private normal through the wiper 72, front contacts of relays 61 and 60, springs 102 and 103, upper winding of relay 101, springs 104 and 105, and springs of relay 48 to ground. Relay 101 energizes to open the circuit of the magnets at springs 92, closes a locking circuit for relay 61 through springs 106 and 107, connects ground from springs of relay 48 through springs 108 through its own lower winding and to the private wiper 72 to guard the called line from seizure. Relay 101 also connects the called line through con-

acts 109 and 110 to the ringing machine R on one side and to a winding of the ring cut off relay 111 on the other side. The called subscriber will now be signalled and upon answering relay 111 pulls up to disconnect the ringing machine from the called line and lock itself to ground through springs 112. Relay 111 also connects the called line to the windings of back bridge relay 113, which is energized over the called line to supply talking battery thereto and to reverse the connections of the line relay 47 to the calling line for metering or other purposes. Conversation may now proceed over the heavy conductors shown and over the line wipers 71 and 73 of connector H to the called line.

It will be understood therefore that I have provided a very efficient and novel type of large capacity switches in which the method of extending connections to large groups of subscribers is entirely new. For instance if the number 111 is called the connection will be extended over the wipers 17 and 18 of the selector D to a line in the first level of the upper bank to an idle one of a plurality of connectors similar to H which may have access to 400 lines either in some other branch exchange or in another subdivision of the same exchange and the connector seized will then be operated to extend the connection to the line terminating in the first set of contacts in the first level of the bank which is accessible to wipers 62, 63 and 64, as in this call none of the switching relays will be energized. That is, if any even number of impulses are sent to the selector D the switching relay 29 will be energized and the call will extend over the alternate set of wipers 20, 21 and 22 while if an odd number of impulses are sent the relay 29 will not be energized. In the same manner if the connector H is operated by two odd series of impulses then neither relay 60 nor 61 will be operated and connection will be extended over the normal set of wipers 62, 63 and 64 while if one odd and one even set are delivered to H then relay 60 will not be energized but relay 61 will be, if the even set of impulses are sent last, and connection will be extended over the wipers 65, 66 and 67. If one even and then one odd number of impulses are delivered then relay 60 will energize alone and connection will be extended over wipers 68, 69 and 70, while if two odd numbers of impulses are delivered both relays will remain energized and the connection will extend over the wipers 71, 72 and 73 as described.

Having fully described and ascertained features and aspects of my invention, what I consider to be new and desire to have protected by Letters Patent will be pointed out in the appended claims.

What I claim as my invention is:

1. In a telephone system an automatic switch having a plurality of sets of wipers, lines accessible to each set of wipers, means for operating said switch in accordance with a plurality of the digits of a called number to extend a connection over one of said sets of wipers to one of the lines accessible thereto, the set of wipers over which the connection is extended depending upon the number of impulses in each digit. 75

2. In a telephone system, an automatic switch, a plurality of sets of wipers, a plurality of lines accessible to each set of wipers, a magnet for moving said sets of wipers into engagement with any of the lines accessible thereto, a line leading to said switch, a relay for switching said line from one set of wipers to the other, means for sending impulses of current over said line to operate said switch, and means for delivering each alternate impulse to said switching relay. 80

3. In a telephone system, an automatic switch, a plurality of sets of wipers for said switch, a plurality of groups of trunk lines accessible to each set of wipers, means for transmitting a series of impulses to said switch to operate the same to position each set of wipers in front of the first trunk line of a group, and means dependent upon whether an odd or even number of impulses are transmitted for determining which set of wipers is to be used for extending a connection. 95

4. In a telephone system, an automatic switch, a plurality of sets of wipers for the switch, an operating magnet for operating all of said wipers, and a switching relay for switching the connection from one to the other of said sets of wipers, means for transmitting a series of impulses to said switch, and means for delivering the impulses alternately to the operating magnet and to the switching relay. 105

5. In a telephone system, an automatic switch, a plurality of sets of wipers for the switch, an operating magnet for operating all of said wipers, a switching relay for switching the connection from one to the other of said sets of wipers, means for transmitting a series of impulses to said switch, and means for delivering the impulses alternately to the operating magnet and to the switching relay, the set of wipers over which a connection is extended depending upon whether the last impulse was delivered to the switching relay or to the operating magnet. 110 115 120

6. In a telephone system, an automatic switch having a plurality of sets of wipers and a line relay, means for sending a plurality of series of impulses to said line relay to control the switch, a pair of operating magnets and a pair of switching relays, means for causing the line relay to first operate one magnet and one relay alternately and 125 130

to then operate the other magnet and relay alternately, and means dependent upon the number of impulses in each series for causing said switching relays to determine the 5 set of wipers to be used in extending a connection from the switch.

7. In a telephone system, an automatic switch, a line leading thereto, a plurality of sets of wipers for the switch, a line relay for 10 the switch for controlling said switch to step all of the wipers first to a group and then to a line in that group in response to two series of impulses, a pair of switching relays, one of said relays operated by part of 15 the impulses of the first series and the other by part of the impulses of the second series, said relays operating in conjunction to switch the line to a predetermined one of said sets of wipers.

20 8. In a telephone system, an automatic switch, a line leading thereto, a plurality of sets of wipers for the switch, a line relay for the switch for controlling said switch to step all of the wipers first to a group and 25 then to a line in that group in response to two series of impulses, a pair of switching relays, one of said relays operated by every alternate one of the impulses of the first series and the other by every alternate one 30 of the impulses of the second series, said relays operating in conjunction to switch the line to a predetermined one of said sets of wipers.

9. In a telephone system, an automatic 35 switch operated in response to certain of the digits of a called number to extend a connection from a line, a line relay for the switch operated by the impulses, an operating magnet, a switching relay, and a plurality of 40 sets of wipers for the switch, means for causing the line relay to first operate the magnet to step the wipers one step and to then operate the relay to switch the line to a set of wipers, and to then again operate the magnet to step the wipers a second step and 45 switch the line to another set of wipers.

10. In a telephone system, an automatic switch having a plurality of banks of contacts accessible thereto, a set of wipers having access at the same time to all the contacts in one bank and another set having access to the contacts in another bank, means for sending a series of impulses to said 50 switch to operate the same to move both sets of wipers simultaneously to particular sets of contacts in their associated banks, and means responsive to said series of impulses and controlled over circuits excluding 55 said wipers for determining which set of 60 wipers is to be used.

11. In a telephone system, an automatic switch having a plurality of sets of wipers each having access to a different group of 65 trunk lines, means for sending a series of impulses to said switch to move said wipers,

only a part of said impulses being used to step the wipers, the remainder being used to select a set of wipers for use.

12. In a telephone system, an automatic switch having trunk lines accessible thereto 70 divided into main and sub-groups, means for operating said switch by a single series of directive impulses to select a sub-group of lines and a relay controlled while the switch is being thus operated independent 75 of the mechanical operation of the switch for selecting a desired main group of lines.

13. In a telephone system an automatic switch having lines accessible thereto divided into main and sub-groups, means for operating said switch by two series of impulses to select a desired sub-group of lines and a desired line in the group, and wiper selecting means controlled while the switch is being thus operated in response to the second series for determining in which main group the selected sub-group is to be connected with.

14. In a telephone system an automatic switch having trunk lines accessible thereto 90 divided into groups, sets of wipers for the switch, each set having access to one group, means for sending a series of operating impulses to the switch to move the wipers simultaneously into position adjacent to the first trunk lines of their associated groups, and means for selecting a set of said wipers, responsive to a portion of said operating impulses.

15. In a large capacity automatic telephone system, a subscriber's impulse transmitter capable of transmitting twenty impulses, an automatic group selecting and trunk hunting switch having double sets of wipers and ten groups of lines accessible to 100 each wiper set, and mechanism in said switch responsive to a single series of impulses for advancing said wiper sets simultaneously 105 into initial hunting position before groups of contacts and for selecting a particular set 110 of wipers for use.

16. In a large capacity automatic telephone system, a subscriber's impulse transmitter capable of transmitting twenty impulses, an automatic switch having double 115 sets of wipers, and ten groups of lines accessible to each wiper set, and mechanism in said switch responsive to a single series of impulses for selecting whole groups of contacts two at a time by advancing said wiper 120 sets simultaneously and for selecting one of any two selected groups by connecting up one or the other of said wiper sets depending on the number of impulses in the series.

17. In an automatic telephone system, an 125 automatic switch having two sets of wipers and a plurality of groups of contacts accessible to each wiper set, a sender for transmitting a series of impulses to said switch comprising twice as many impulses as there 130

6
are groups of contacts accessible to each wiper set, stepping mechanism responsive only to the odd impulses of said series for advancing both sets of wipers to groups of 5 contacts, and mechanism responsive to the even impulses of said series to select a desired set of wipers.

18. In an automatic telephone system, an automatic switch having two sets of wipers 10 and a plurality of groups of contacts accessible to each wiper set, a sender for transmitting a series of impulses to said switch comprising twice as many impulses as there are groups of contacts accessible to each wiper 15 set, mechanism for advancing both sets of wipers to groups of contacts simultaneously, wiper set selecting mechanism, and relays for causing said mechanisms to respond alternately to said series of impulses.

19. In an automatic telephone system, an automatic switch having two sets of wipers, one normally connected and the other normally disconnected, groups of contacts accessible to each set of wipers, means for transmitting series of impulses to said switch, means responsive to either of two different series of impulses for advancing both sets of wipers to the same groups of contacts in their respective banks, and means responsive 30 to only one of said series of impulses for disconnecting the normally connected set of wipers and for connecting the normally disconnected set of wipers.

20. In a telephone system, an automatic switch having two sets of wipers and a plurality of groups of contacts accessible to each set, means for transmitting a series of impulses to said switch comprising twice as many impulses as there are groups of contacts accessible to each wiper set, group selecting mechanism in said switch responsive only to half of the impulses of said series, and wiper set selecting mechanism in said switch responsive to the other half.

21. In a telephone system, an automatic switch having two sets of wipers and a plurality of groups of contacts accessible to each set, a repeating line relay in said switch, means for transmitting a series of 50 impulses to said line relay, group selecting

mechanism and wiper set selecting mechanism in said switch, and separating means for causing said line relay to repeat part of the impulses of said series to said group selecting mechanism and the rest of the impulses to said wiper set selecting mechanism.

22. In a telephone system, an automatic switch having two sets of wipers and magnets for operating them, a wiper switching relay operated or not operated depending on 60 which wiper set is to be used, groups of contacts accessible to each wiper set, a sender for transmitting a series of impulses to said switch, an impulse repeating relay in said switch, and means controlled by said relay 65 for relaying certain of a series of impulses to one of said operating magnets and for relaying the other of said impulses to said wiper switching relay.

23. In a telephone system, an automatic 70 switch having trunk lines accessible thereto divided into main and sub-groups, means for operating said switch by a single series of directive impulses to select corresponding sub-groups of lines in the different main 75 groups and a relay controlled while the switch is being thus operated for selecting a desired main group.

24. In a telephone system, an automatic switch having a plurality of wiper sets, 80 a magnet for positioning said wiper sets, a line relay for repeating impulses from a calling line to said magnet, and means thereafter responsive to an impulse repeated by the line relay, while the wipers remain inert, 85 to select a particular wiper set.

25. In a telephone system, an automatic switch having normally connected and disconnected wiper sets, respectively, a relay for switching from one wiper set to the other, 90 groups of contacts accessible to each of said wiper sets, impulse operated mechanism for moving both of said wiper sets into selective relation with contact groups served by them, and means for thereafter operating said relay over a circuit excluding said wipers.

Signed by me at Chicago, Cook County, Illinois, this 30th day of October, 1918.

EMIL JACOBSEN.
